US0D1016679S

(12) **United States Design Patent** (10) Patent No.: **US D1,016,679 S**
(45) Date of Patent: ** Mar. 5, 2024

(54) **DASHBOARD FOR ELECTRIC BICYCLES**

(71) Applicant: **GUANGDONG GOBAO ELECTRONIC TECHNOLOGY CO., LTD**, Guangdong (CN)

(72) Inventors: **Qifang Zeng**, Dongguan (CN); **Linqiang Lan**, Dongguan (CN); **Kang Shen**, Dongguan (CN)

(73) Assignee: **GUANGDONG GOBAO INTELLIGENT TECHNOLOGY CO., LTD.**, Dongguan (CN)

(**) Term: **15 Years**

(21) Appl. No.: **29/808,457**

(22) Filed: **Sep. 20, 2021**

(30) **Foreign Application Priority Data**

Jul. 2, 2021 (CN) 202130417026.7

(51) LOC (14) Cl. **12-11**

(52) U.S. Cl.

USPC **D12/114**

(58) **Field of Classification Search**

USPC D12/110, 111, 112, 114, 117, 118, 119, D12/120, 126

(57) **CLAIM**

The ornamental design for a dashboard for electric bicycles, as shown and described.

DESCRIPTION

FIG. 1 is a perspective view of a dashboard for electric bicycles showing my new design;

FIG. 2 is another perspective view thereof;

FIG. 3 is a front elevation view thereof;

FIG. 4 is a rear elevation view thereof;

FIG. 5 is a left elevation view thereof;

FIG. 6 is a right elevation view thereof;

FIG. 7 is a top plan view thereof;

FIG. 8 is a bottom plan view thereof;

FIG. 9 is an enlarged view of the selected portion 9 in FIG. 1;

FIG. 10 is an enlarged view of the selected portion 10 in FIG. 5;

FIG. 11 is an enlarged view of the selected portion 11 in FIG. 7; and,

FIG. 12 is an enlarged view of the selected portion 12 in FIG. 8.

The broken lines shown in the figures depict portions of the dashboard for electric bicycles that form no part of the claimed design.

1 Claim, 12 Drawing Sheets
